SLAT FEED

Gerald C. Paxton, Santa Ana, Calif., assignor to
 Food Machinery Corporation, San Jose, Calif.,
 a corporation of Delaware

Application December 28, 1936, Serial No. 117,709

10 Claims.

(Cl. 1—14)

This invention relates to improvements in box making machines and has particular utility in the general type of machine shown in U. S. Letters Patent No. 1,884,333 issued February 9, 1932

5 to E. C. Northrup on a Box machine.

The machine disclosed in the aforesaid patent is adapted for nailing the two sides and bottom onto the box ends (and, if desired, onto a middle partition) to form a shipping box such as those 10 commonly used for shipping oranges or other kinds of fresh fruits. When thus assembling these boxes said machine was provided with means for holding the ends and middle partition of the box properly positioned beneath the nailing mechanism while slat feeding arms removed slats from the lower end of a magazine containing these and delivered these slats into position over the box ends and partition where the nailing mechanism nailed these slats to the box ends

20 and partition. Each of the sides and bottom of the box is formed in said machine by such an operation, the partially formed box being automatically rotated 90° between successive operations.

25 The aforesaid machine was adapted to make boxes varying as to width and depth with the limitation, however, that where the width greatly exceeded the depth of the box some means had to be provided to prevent the slat carrying devices plunging through the bottom of the box at the time of feeding the last side onto the box ends. The reason for this was that when these slat carrying arms were made of sufficient length to carry the relatively wide bottom slats into assembling positions, these arms were so long that if projected an equal distance into the machine when carrying the relatively narrow slats for the final side these arms would be poked right through the bottom just previously nailed into 35 place.

40 One means for overcoming this difficulty is disclosed in the aforesaid patent and it is an object of this invention to provide an improved means for this purpose which is relatively inexpensive, simple and satisfactory in operation.

In order to simplify the disclosure in this application I have shown the invention herein as applied to the machine illustrated in the aforesaid patent. The old parts of said machine included in the drawing in this case are identified by the same reference characters as employed for this purpose in said patent.

The manner of accomplishing the aforesigned object, as well as further objects and advantages will be made manifest in the following

description taken in connection with the accompanying drawing, in which:

Fig. 1 is a fragmentary cross sectional view of the nailing machine shown in the aforesaid U. S. Letters Patent and having incorporated therewith a preferred embodiment of the invention, this view showing said machine about to nail the first side on a box.

Fig. 2 is a fragmentary view similar to, although more restricted in scope than Fig. 1, and showing said machine about to nail the bottom on said box.

Fig. 3 is an enlarged fragmentary view similar to Fig. 2 showing the machine during the operation of applying the final side to the box.

Fig. 4 is a still further enlarged cross sectional view taken on the line 4—4 of Fig. 1 and illustrating the construction of one of the slat feeding arms.

In referring specifically to the drawing no attempt will be made to completely describe the old features of the machine shown therein as they are already thus described in the U. S. Letters Patent above referred to. However, it may be noted for our present convenience that this machine has a frame 2 upon which is supported a central stack 10 of horizontally disposed slats adapted to form sides and bottoms of boxes, these slats being prearranged in wide and narrow widths in the sequence of their use.

Horizontally slidable on the frame 2 beneath the stack 10 is a slat feeding carriage 11 which is reciprocated at regular intervals over a fixed path by an arm 12 throughout the operation of the machine. It will be noted that the aforesaid patent discloses an optional mechanism including a chain 117, a cam 116, and a roller 115 for causing uniform reciprocations of a pitman 13 to be transmitted to a power arm 12 in such a manner that there will be a variation in the length of successive reciprocations of the arm 12. The use of this mechanism is optional, however, and it is not required for the manufacture of lemon boxes such as those shown being made in the operation views of the drawing 45 of said patent. Neither is the use of this mechanism required in a nailing machine employing the invention disclosed in the present application.

In order to render this mechanism inoperative, it is merely necessary to disconnect the chain 117 when the cam 116 is positioned so that the high portion thereof is disposed beneath the roller 115 as shown in Fig. 3 of the patent drawing. When said optional mechanism is thus disconnected, the uniform reciprocations of the pitman 50 55

man 13 are transmitted to the power arm 12 so as to cause the latter to reciprocate uniform distances in the operation of the machine.

Just in advance of the forwardmost position of the carriage 11 is located a box assembly space. Just beneath this space is a nailing table 15 and above this space are located nailing chucks 16 suitably associated with nail drivers 60 and mechanism for operating the latter. As the carriage 10 11 reciprocates, lugs 74 thereon feed box ends 6 from suitable magazines (not shown) into upright positions over and resting upon the nailing table 15 as shown in Fig. 1. These box ends 6 are only fed by the lugs 74 once for each three 15 reciprocations of the carriage 11 as is made clear in the description of said machine in said patent. Mounted on the frame 2 over the nailing table 15 are discs 17 which are provided with suitable mechanism (not shown) which causes these discs 20 to grip the box ends 6 and rotate these ends 90° between successive nailing operations.

A feeding of slats from the stack 10 into position over the box ends 6 is accomplished by a pair of shock feeding arms 86 which are mounted 25 for pivotal rotation on their own axes on members 94 which are in turn horizontally pivoted at 95 on the carriage 11 so that the members 94 and rotatable arms 86 can be lowered at the end of the forward stroke of the carriage 30 11 to return clear of the delivered slats.

The arms 86 are normally held up in horizontal position by pivotal latches (not shown) which are kicked by striking adjustable stop screws (not shown) on the fixed frame of the 35 machine as the members 94 arrive at their forwardmost positions. On the return stroke of the carriage 11 a pivoted lever 99 provided on each of the members 94 is shifted upwardly by engagement with a cam (not shown) so as to 40 return that member 94 and the arm 86 mounted thereon upward to their horizontal positions in which they are automatically latched and retained throughout the forward movement of these with the carriage 11 which follows.

45 As the levers 99 elevate the levers 94 to horizontal positions they also rotate the arms 86 one third of a revolution. Each of the arms 86 is composed of three ribs 86a, 86b and 86c on each of which are mounted hooks 87 for engaging slats and picking these from the lower end of the stack 10 while the carriage 11 is travelling forwardly with the arms 86 held upwardly in horizontal position. After each one third revolution given to the arms 86 as above noted 50 a different pair of ribs of these arms is disposed upwardly. The hooks 87 are variously positioned on the three ribs of the arms 86 in accordance with the desired number and space of slats.

55 On ribs 86a and 86b the hooks 87 are spaced 60 apart relatively short distances so as to properly position narrow slats 10a when forming the sides of the box. On rib 86c of each of the arms 86 the hooks 87 are spaced apart a relatively long distance so as to properly position a pair of 65 relatively wide slats 10b in forming the bottom of the box.

Slidably mounted on the opposite face of each rib 86c from the face thereof on which hooks 87 are mounted, is a telescopic slat support 130. 70 This support is preferably formed of sheet metal, has a head 131 on the forward end thereof and is provided with slots 132 through which cap screws 133 extend, the latter being received in threaded holes in the rib 86c. As shown in Fig. 75 4 the portions of the cap screws 133 which lie in

the slots 132 are surrounded by sleeves 134. Connecting between the forwardmost of the cap screws 133 and a pin 135 mounted in the support 130 is a contractile coil spring 136 which yieldably maintains the support 130 in its forwardmost position in which it is shown in Figs. 1 and 2.

Operation

To begin with, the machine disclosed in the drawing is supplied with a stack of slats 10 made up of groups of slats, each group of which comprises two slats 10b with two slats 10a on the top thereof and two slats 10a on the bottom thereof. The hoppers for the box ends 6 are furnished with a supply of the latter so that when the machine is started the first reciprocation of the carriage 11 feeds a pair of the box ends 6 into the position in which these are shown in Fig. 1.

As previously pointed out the members 94 and arms 86 are lifted into horizontal position as the carriage 11 approaches its rearwardmost position and are allowed to thus remain during the forward travel of the carriage. At the same time the feeding arms 86 are lifted to horizontal position they are rotated one third revolution. This rotation takes place in the direction of the arrow 140. At the start of the operation of the machine the ribs 86b of the shock feeding arms 86 are disposed upwardly as shown in Fig. 4. During the first forward movement of the carriage 11 therefore, the hooks 87 on this rib engage and strip from the bottom of the stack 10 the lowermost pair of slats 10a and feed these into the positions in which they are shown in Fig. 1, the lugs 74 simultaneously feeding the box ends 6 into the machine.

As already noted, as the carriage 11 reaches its forwardmost position the mechanism which supports the members 94 and arms 86 in horizontal position automatically collapses to permit the members 94 and arms 86 to swing downwardly into the inclined position in which they are shown in Fig. 1 and they remain in this position while the carriage is being withdrawn to its rearwardmost position where they are again returned to horizontal.

Immediately following the lowering and withdrawal of the arms 86 as indicated in Fig. 1, the mechanism supporting the nail chucks 16 and drivers 60 sets these in motion to lower the nail chucks onto the slats 10a just delivered by the arms 86 and nail these slats to the ends 6.

Immediately following each nailing operation 55 the chucks 16 are lifted from the work and the latter is rotated by the discs 17 one quarter revolution after which the discs relax their hold on the box ends 6 and the table 15 is automatically elevated or lowered to support the work at such a height that the upper surface thereof to be engaged by the chucks 16 in the next proceeding nailing operation will always be in the same horizontal plane.

Due to the partial rotation of the slat feeding arms 86 the second forward movement of the latter finds the ribs 86b disposed in upward position as shown in Fig. 2, so that the hooks 87 of these ribs engage and strip from the stack 10 the lowermost pair of wide slats 10b in the stack. 70 Owing to the width of the slats 10b the front edge of the foremost slat extends a considerable distance beyond the front ends of the shock feeding arms 86 and rests upon the heads 131 of the supports 130. During the latter portion of the 75

forward movement of the carriage 11 the lugs 74 engage the rear edges of the work and shift this forwardly so that when the feeding arms 86 are lowered slats 10b supported thereon are left 5 in the proper positions on the work for nailing thereto. Fig. 2 clearly shows that the support provided by the members 130 for the forward edge of the leading slat 10b is necessary in order that this slat may be properly fed into place for 10 assembly with the box.

When the next forward movement of the feeding arms 86 takes place, the latter have been rotated another third revolution bringing rib 86a into upward position and the work has been rotated another quarter revolution into the position in which this is shown in Fig. 3. Here it is seen that the bottom slats 10b which have just 15 been nailed in place on the box lie directly in the path of the telescopic support 130 as these move 20 forwardly with the arms 86 in order to deposit a pair of the narrow slats 10a on the box ends 6 in the process of forming the final side on the box. The resistance of the box bottom to the 25 continuous forward movement of the supports 130 causes these supports to be telescoped upon the feeding arms 86 thus stretching the springs 136, this telescoping action being clearly shown in Fig. 3.

Upon the withdrawal of the arms 86 from 30 within the completed box the contraction of the springs 136 extend the supports 130 to their original extended positions in which they are shown in Figs. 1 and 2 and these supports remain thus extended until they are brought into 35 engagement with the bottom of the next box to be assembled in the machine in the same manner as has just been described.

It will be seen from the foregoing disclosure that I have provided a very simple and economical expedient for solving the problem of feeding 40 bottom and side slats which differ considerably in width, into assembling positions in an automatic box making machine such as shown in the aforementioned U. S. Letters Patent, without 45 breaking the bottom of the box when feeding in the slats for forming the final side to be assembled with the box.

What I claim is:

1. In an automatic box making machine the 50 combination of: a reciprocating shook feeder adapted to pick a shook from beneath a pile and carry it to box assembling position; means on said feeder for engaging and stripping pieces of shook from beneath said pile; a telescopic support mounted on said feeder and disposed beyond the forward end thereof when in extended position; and means for yieldably urging said support into extended position.

2. In an automatic box making machine the 55 combination of: a reciprocating shook feeder adapted to pick a shook from beneath a pile and carry said shook to box assembling position, said feeder being adapted to so feed shooks varying substantially in width; and means for supporting the front edge of a substantially wider shook carried by said feeder said last recited means being adapted to yield towards said feeder when encountering a substantial resistance.

3. In an automatic box making machine the 60 combination of: means for positioning a pair of heads for receiving in the order named an initial side, a bottom and a final side, said sides and

bottom being formed of slats; a magazine adapted to hold relatively narrow slats for forming said sides and relatively wide slats for forming said bottoms; means for nailing said slats to said box heads when said slats are in proper position relative to said heads; a reciprocating shook feeder shiftable beneath said magazine, to pick said slats from said magazine and carry said slats into position to be nailed to said box heads by said nailing means; and means carried 10 on said feeder for supporting the forward edge of a bottom slat carried on said feeder, said means yielding towards said feeder upon engaging the bottom of said box when said feeder moves into position for positioning the side 15 slats for the final side of said box.

4. In an automatic box making machine, the combination of: a reciprocating shook feeder adapted to pick a shook from beneath a pile and 20 having a plurality of sets of slat engaging dogs; means for selectively presenting said sets of dogs in slat engaging positions; and slat support means mounted on said feeder, said means being adapted to support the front edge of a wide 25 slat and to yield towards said feeder when encountering a substantial resistance.

5. In an automatic box making machine the combination of: a reciprocating shook feeder adapted to pick a shook from beneath a pile and 30 carry it to box assembling position; means on said feeder for engaging and stripping pieces of shook from beneath said pile; a telescopic shook support slidably mounted on said shook feeder and disposed beyond the forward end thereof 35 when in extended position; and spring means for yieldably urging said telescopic support into extended position.

6. A combination as in claim 2 in which the 40 shook support means last recited therein is slidably mounted on said shook feeder; and spring means for yieldably urging said shook support means into extended position.

7. In an automatic box making machine the combination of: a pair of reciprocating shook 45 feeding arms adapted to pick slats from beneath a pile of the same and carry said slats to box assembling positions; and means on said arms for supporting the front edge of a slat carried by said arms, said support means being adapted to 50 yield in the direction of said arms when encountering a substantial resistance.

8. In an automatic box making machine the combination of: a reciprocating shook feeder adapted to pick a slat from beneath a pile and 55 carry it to box assembling position, said feeder including an arm provided with three substantially radial ribs, shook engaging hooks on said ribs; and a telescopic member on said feeder for supporting the front edge of a slat disposed forwardly of the front end of said feeder said member being adapted to yield towards said feeder upon encountering a substantial resistance.

9. A combination as in claim 8 in which said 60 telescopic member is slidably disposed upon one 65 of said ribs on the opposite side of said rib from the side thereof on which said hooks are mounted.

10. A combination as in claim 1 in which said 70 telescopic support is formed of sheet metal and has a head bent therefrom at its forward end.
